DESIGN FOR A SLIDE FASTENER CLOSURE

Ralph Kay, New York, N. Y.

Application September 16, 1939, Serial No. 87,246

Term of patent 3½ years

To all whom it may concern:

Be it known that I, Ralph Kay, a citizen of the United States of America, residing in New York city, in the Borough of Manhattan, county and State of New York, have invented a new, original, and ornamental Design for a Slide Fastener Closure, of which the following is a specification, reference being had to the accompanying drawing, forming part thereof wherein:

Figure 1 is a plan view of a slide fastener closure showing my new design.

Figure 2 is a sectional view on line 2—2 of Figure 1.

I claim:

The ornamental design for a slide fastener closure, substantially as shown.

RALPH KAY.
